(57) **CLAIM**

The ornamental design for a child safety seat for motor cars, as shown and described.

DESCRIPTION

FIG. 1 is a perspective view of a child safety seat for motorcars in accordance with my new design;

FIG. 2 is a side perspective view of a first side of the child safety seat of FIG. 1;

FIG. 3 is a side perspective view of a second side of the child safety seat of FIG. 1;

FIG. 4 is a rear perspective view of the child safety seat of FIG. 1;

FIG. 5 is a front perspective view of the child safety seat of FIG. 1;

FIG. 6 is a top perspective view of the child safety seat of FIG. 1; and,

FIG. 7 is a bottom plan view of the child safety seat of FIG. 1.

In the drawings, the broken lines represent portions of the article that form no part of the claimed design.

1 Claim, 7 Drawing Sheets
